Primary Examiner — Brian N. Vinson*(74) Attorney, Agent, or Firm* — Michael Best & Friedrich LLP(57) **CLAIM**

The ornamental design for a stand light, as shown and described.

DESCRIPTION

FIG. 1 is a perspective view of a stand light showing our new design in a stowed configuration; and,
FIG. 2 is a perspective view of a stand light thereof, in a deployed configuration.

The broken line disclosure represents portions of the stand light which form no part of the claimed design.
